UNITED STATES PATENT OFFICE

2,600,468

PACKER FOR WELLS

Neil T. Breaux, Houston, Tex.

Application July 16, 1948, Serial No. 39,081

6 Claims. (Cl. 166—12)

1

This invention relates to a packer for wells. An object of the invention is to provide a packer of the character described specially designed for use in forming a seal between the outer well casing and an inner producing string of tubing and which embodies novel means for expanding the packer to form an effective seal between the casing and tubing.

The type of packer herein described is also very effective in carrying on what is commonly known as a squeezing operation, that is for forcing cement out through perforations in the casing to seal off water or gas from the producing strata.

The type of packer assembly herein described may be readily set at any selected point in the casing by an upward pull on the tubing and also readily released by an appropriate manipulation and upward pull on the tubing and the construction is such that the assembly may be readily released and reset at an upper or a lower elevation and is consequently very useful in testing the casing for leaks.

The packer assembly may, if desired, be reversed, end for end, in position in the well and will operate effectively in reverse position.

It is a further object of the invention to provide equipment of the character described wherein in the operating string and packer body may be removed in case the packer assembly becomes stuck in the well.

Other objects and advantages will be apparent from the following specification which is illustrated by the accompanying drawings, wherein:

Figure 1 is a side elevation, partly in section, of the assembly showing the packer collapsed and being lowered into the well casing.

Figure 2 is a side elevation, partly in section, showing the packer set, or expanded.

Figure 3 is a side elevation, partly in section, showing the assembly in released position for withdrawal of the assembly and the equipment beneath from the well.

Figure 4 is a fragmentary, elevational view of the inner tubular section of the packer body.

Figure 5 is a cross-sectional view taken on the line 5—5 of Figure 2, and

Figure 6 is a side elevation, partly in section, showing the operating string in position to be released, from the packer assembly, and from the equipment beneath, and withdrawn from the well, in case said assembly becomes stuck in the well.

Referring now more particularly to the drawings wherein like numerals of reference design-

2

nate the same parts in each of the figures, the numeral 1 designates the inner section of the packer body and telescoped over the lower end of said inner section there is the outer tubular section 1a of said packer body.

The inner tubular section 1 may be connected to the operating string 2 above by means of a reducing coupling 3 whose upper end is threaded onto said string and whose lower end is threaded onto the upper end of the inner section 1 of the packer body.

Threaded onto the lower end of the section 1a by coarse, left hand, threads 4 there is a tubular expander body 5 whose upper end is formed with an annular, wedge shaped upwardly directed expander 6 which is spaced outwardly from the packer body.

Around the upper end of the body section 1 and threaded onto a reduced externally threaded neck of the coupling 3 there is a tubular cage 7. It should be here noted that the threads connecting said cage and the coupling 3 are coarse right hand threads which may be readily unscrewed. The cage 7 is provided with vertically extended external sockets 8 to receive the friction blocks 9. These friction blocks are seated on coil springs 10 which hold the blocks outwardly in frictional contact with the outside casing, as shown in Figure 2.

Fitted into the lower end of the cage 7 and suitably swivelled thereon by a pin and slot connection there is a slip supporting ring 11 and depending from this ring there are the wedge shaped slips 12 which are suspended from the ring 11 by the links 13 pivoted at their upper ends to the ring 11 and at their lower ends to the corresponding slips 12.

Around the inner section 1 of the packer body there is a locking ring 14 which works between said section 1 and the tubular cage 7. It is located between an upper inside annular shoulder 15 of the valve cage and an external annular shoulder 16 of the inner section 1 so as to limit the relative longitudinal movement of these parts. This locking ring is best shown in its locking position in Figure 6.

There is a tubular slip expander indicated generally by the numeral 17 and which is fitted around the outer section 1a of the packer body and whose external surface is upwardly tapered and with which the slips 12 have sliding dovetailed connections, as 18.

The slips 12 are prevented from detachment from the expander by means of pins 19 which are threaded into the expander and whose outer

ends are engageable with lower inside shoulders 20 at the lower ends of the slips 12. The inner ends of the pins 19 are reduced in diameter and extend inwardly into vertical grooves 19a in the external surface of the outer body section 1a, so that these inner reduced ends may be sheared off to permit the tubular section 1a to be rotated relative to the packer and slips in the event that the packer assembly should become stuck in the well.

The external surface of the slips are provided with teeth which are pitched upwardly and outwardly and upon downward movement of the slips relative to the expander said slips will be expanded into engagement with the outer casing, as shown in Figure 2.

There is a packer supporting ring 21 of cage like construction and whose upper end is screwed into the lower end of the expander 17. Beneath the supporting ring 21 there is a resilient sleeve like packer 22 which may be formed of rubber or rubberized material and whose upper end is secured to said ring 21.

The lower end of the packer 22 is provided with a deep, annular end slot 23 in alignment with the expander 6 and adapted to receive said expander, upon setting of the packer, to expand the lower end of the packer, as shown in Figure 2.

The expander 17 is provided with an inside upwardly directed shoulder 24 and the outer body section 1a has an external annular shoulder 25 above the shoulder 24 and engageable therewith to interlock the expander with the packer body and to limit its longitudinal movement upwardly relative to said body to prevent separation of these parts.

The packer body is also provided with upper and lower annular seals 26 and 27 between said sections.

Between the upper end of the section 1a and the annular shoulder 16 and surrounding the section 1 there is a relatively strong coil spring 28 which acts as a resilient bumper to relieve the mechanism of shocks during the manipulation of the assembly.

The lower end of the inner body section 1 is provided with an external longitudinal slot 29 whose upper end is provided with a laterally turned notch 30. In the present illustration this notch is turned to the left. The outer section 1a carries a pin 31 which works in said slot and when turned into the notch 30 the inner and outer sections 1 and 2 will be maintained against longitudinal movement as, for example, when the assembly is being lowered into the well casing, as shown in Figure 1, or while setting the packer, and spring 28 maintains pin 31 seated in notch 30.

The assembly is shown in Figure 1 as being initially lowered into the well casing with the lower end of the coupling 3 screwed into the upper end of the cage 7 and with the lower end of the packer body screwed into the upper end of the expander body 5 and with the pin 31 seated in the notch 30.

As so assembled the packer assembly may be lowered into the casing 1 to the desired location without danger of the premature setting of the packer.

When a point is reached where it is desired to set the packer the operating string 2 may be turned to unscrew the lower end of the coupling 3 from the upper end of the cage 7. This may be done without difficulty because these parts are connected by coarse threads. During this

operation the expander body 5 will turn with the packer body 1, 1a. Thereupon the operating string 2 may be pulled upwardly and the friction of the blocks 9 against the casing will hold the cage 7 and the slips 12 against upward movement but the packer body, whose sections are interlocked by the pin 31, together with the expander body 5 will move upwardly moving the packer and the expander 17 upwardly thus expanding the slips 12 into engagement with the casing which will arrest the upward movement of the slips and expander and upon further upward movement of the string 2 the expander 6 will move further upwardly into the slot 23 and will very effectively expand the packer so as to form a fluid tight seal between the packer and casing as well as the packer and the surrounded packer body.

The expander body 5 also forms a coupling providing for the connection of well equipment beneath to the packer assembly.

Should it be desired to remove the packer from the well the operating string 2 may be turned to unseat the pin 31 from the notch 30 and then pulled upwardly into the position indicated in Figure 3 thus elevating the slips 12 relative to the slip expander 17 so as to release the slips from the outer well casing and upon further upward movement the pin 31 will be engaged by the lower end of the slot 29 and the entire packer together with the equipment beneath may be withdrawn from the well.

Should the packer assembly become stuck in the well bore so that it cannot be removed, the operating string 2 may be turned to the right, or in a clockwise direction so as to shear the pins 19 and unscrew the lower end of the outer section 1a of the packer body from the expander body 5, as illustrated in Figure 6, thus detaching the packer body from the expander body 5 and with the reducing coupling 3 disengaged, or unscrewed, from the upper end of the cage 7 and with the pin 31 unseated from the notch 30, as indicated in Figure 6, the operating string 2 and packer body may be pulled upwardly shearing the shoulder, or rib, 15 and the operating string 2 and the body 1, 1a may be withdrawn from the well thus leaving the stuck equipment in the well to be later drilled out.

The inner ends of the pins 19 project into the vertical grooves 19a of the body section 1a, as hereinabove stated, and this prevents the packer body from turning independent of the slips 12 and the slip expander 17 on which said slips are mounted.

The complete assembly may be reversed in position in the well with the friction blocks 9 beneath the packer 22 and the equipment will operate equally as well. When so reversed the parts will be connected as shown in Figure 1 but in reverse position. When a point has been reached where it is desired to set the packer, the operating string, which is then connected to the expander body 5, may be lowered. These slips 12 will be held against downward movement by the friction blocks 9. The operating string and the body 1, 1a may then be turned to the right to detach the coupling 3 from the cage 7 and the slip expander 17 will move downwardly and expand the slips into engagement with the well casing and hold the packer 19 against further downward movement while the expander body 5 moves downwardly and the expander 6 will enter the annular slot 23 and this expander 6 will effectively expand the upper end of the

packer 22 and the weight of the string above will further expand said packer to make an effective seal between the packer assembly and the well casing.

The drawings and description disclose what is now considered to be a preferred form of the invention by way of illustration only and not by way of limitation while the broad principle of the invention will be defined by the appended claims.

What I claim is:

1. A packer assembly for wells comprising a packer body, said body having inner and outer tubular sections telescopically arranged, means connecting one of said sections to an operating string above said assembly, one of said sections having a longitudinal slot provided with a laterally extending notch, a pin on the other of said sections extending into said slot and movable into said notch upon relative rotation of the sections in one direction to hold the sections against relative longitudinal movement, said pin being movable out of said notch upon relative rotation of the sections in the other direction to permit relative longitudinal movement of the sections, an expandable packer around the body, a slip expander around the body on the packer, expandible casing-engaging slips around the expander, means slideable on the body and frictionally engageable with the casing to resist rotation thereof when the packer body is rotated and from which the slips are suspended, means initially connecting the friction means with the tubular section connected to the operating string above the assembly and releasable upon rotation of the body relative to the friction means to allow the body and expander to move upwardly relative to the slips to expand the slips into engagement with the casing, and connector means releasably connected to said other of said sections and connected to the well equipment below said assembly, said connector means being engageable with the lower end of the packer upon further upward movement of the body, to expand the packer.

2. A packer assembly for wells comprising, a packer body, said body having inner and outer tubular sections telescopically arranged, means connecting one of said sections to an operating string above the assembly, said inner section having an external longitudinal slot and a lateral notch opening into said slot, a pin on the outer section extending into said slot and movable in the slot upon longitudinal movement of the sections relative to each other, said pin being movable into and out of said notch by rotation of the sections relative to each other and being engageable in said notch to hold the sections against such relative longitudinal movement, an expandable packer around the body, a slip expander around the body on the packer, expandible casing engaging slips around the expander, means slideable on the body and engageable, by friction, with the casing to resist rotation thereof when the packer body is rotated and from which the slips are suspended, means initially connecting the friction means with the tubular section connected to the operating string above the assembly and releasable upon rotation of the body relative to the friction means to allow the body and expander to move upwardly relative to the slips to expand the slips into engagement with the casing and connector means releasably connected to the other of said sections and connected to well equipment below said assembly, said connector means being engageable with the lower end of the packer, upon further upward movement of the body, to expand the packer, said body being rotatable relative to said connector means when the packer is expanded, to release the body from the assembly.

3. A packer assembly for wells comprising, a packer body, said body having inner and outer tubular sections telescopically arranged, means connecting one of said sections to an operating string above the assembly, inter-engaging means on said sections relatively movable upon rotation of the sections relative to each other into and out of a position holding the sections against longitudinal movement relative to each other, an expandible packer around the body, a slip expander around the body on the packer, expandible casing-engaging slips above the expander, friction means engageable with the casing to resist rotation thereof when the packer body is rotated and from which the slips are suspended, releasable means initially connecting the friction means with the body and releasable upon rotation of the body relative to the friction means to allow the body and expander to move upwardly relative to the slips to expand the slips into engagement with the casing, connector means releasably connected to the other of said sections, and connected to well equipment below said assembly, said connector means being engageable with the lower end of the packer and adapted to expand the packer upon further upward movement of the body.

4. A packer assembly for wells comprising, a packer body, said body having inner and outer tubular sections telescopically arranged, means connecting one of said sections to an operating string above the assembly, inter-engaging means on the sections coacting to limit longitudinal movement of the sections relatively to each other and movable upon relative rotation between the sections into and out of a position holding the sections against such relative longitudinal movement, an expandible packer around the body, an upwardly tapering slip expander around the body on the packer, expandible casing-engaging slips around the expander, means engageable by friction with the casing to resist rotation thereof when the packer body is rotated and from which the slips are suspended, releasable means initially connecting the friction means with the body and releasable upon rotation of the body relative to the friction means, said body and expander being movable upwardly relative to the slips upon release of said friction means from the body to expand the slips into engagement with the casing, and connector means releasably connected to the other of said sections, and connected to well equipment below said assembly, said connector means being engageable with the lower end of the packer, upon further upward movement of the body, to expand the packer, said body being rotatable relative to said connector means when the packer is expanded, to release the body from the assembly.

5. A packer assembly for wells comprising, a packer body, said body having inner and outer tubular sections telescopically arranged, means connecting one of said sections to an operating string above the assembly, inter-engaging means on the sections coacting to limit longitudinal movement of the sections relatively to each other and movable upon relative rotation between the sections into and out of a position holding the sections against such relative longitudinal movement, an expandible packer around the body, a slip expander around the body on the packer, expandible casing engaging slips around the ex-

pander, means engageable, by friction, with the casing to resist rotation thereof when the packer body is rotated and from which the slips are suspended, means initially connecting the friction means with the body and releasable upon rotation of the body relative to the friction means, said body and expander being movable upwardly relative to the slips upon release of the friction means from the body to expand the slips into engagement with the casing, connector means releasably connected to the other of said sections, and connected to well equipment below said assembly, said connector means being engageable with the lower end of the packer, upon further upward movement of the body, to expand the packer and interconnecting means on the body and the friction means whereby said friction means and slips may be elevated relative to the expander to release the slips from the casing.

6. A packer assembly for wells comprising, a packer body, said body having inner and outer sections telescopically arranged, means connecting one of said sections to an operating string above the assembly, inter-engaging means on the sections coacting to limit longitudinal movement of the sections relatively to each other and movable upon relative rotation between the sections into and out of a position holding the sections against such relative longitudinal movement, an expansible packer around the body, an upwardly tapering slip expander around the body on the packer, expansible casing engaging slips around the expander, means engageable by fric-

tion with the casing to resist rotation thereof when the packer body is rotated and from which the slips are suspended, releasable means initially connecting the friction means with the body and releasable upon rotation of the body relative to the friction means, said body and expander being movable upwardly relative to the slips upon release of the friction means from the body to expand the slips into engagement with the casing, connector means releasably connected to the other of said sections, and connected to well equipment below said assembly, said connector means being engageable with the lower end of the packer, upon further upward movement of the body, to expand the packer, said body being rotatable relative to said connector means when said packer is expanded, to release the body from the connector means and well equipment below the assembly.
